UNITED STATES PATENT OFFICE

DANIEL J. MAYER, OF BELLEVILLE, NEW JERSEY, ASSIGNOR TO METAL TEXTILE CORPORATION, OF WEST ORANGE, NEW JERSEY, A CORPORATION OF DELAWARE

MACHINE FOR FABRICATING SCOURING DEVICES, MOP HEADS, AND SIMILAR ARTICLES

Application filed July 8, 1931. Serial No. 549,345.

This invention relates to a machine for fabricating scouring devices, mop heads and similar articles; and the invention has reference to an automatic machine for looping a strand upon itself with the center portions intermediate the free loop ends thereof bunched together and secured to provide a central portion or core from which the free loop ends radiate.

10 This invention has for its principal object to provide an automatic machine adapted to loop a strand of material upon itself, and then secure the looped material intermediate the free loop ends, so that the 15 latter will radiate from the thus secured central portion.

More specifically, this invention has for an object to provide an automatic machine for manufacturing scouring devices comprising a metallic gimped carrying strand looped upon itself with the center portions of the strand, intermediate the free loop ends thereof, bunched together and secured to form a central portion or core from which 25 the metal gimped free loop ends radiate in various directions; the scouring device so characterized being of the general type and kind shown in my United States Letters Patent No. 1,713,975, dated May 21st, 1929.

30 Other objects of this invention, not as this time more specifically enumerated, will be understood from the following detailed description of the same.

An illustrative embodiment of the invention is shown in the accompanying drawings, in which:—

Fig. 1 is a side elevation of the novel machine; Fig. 2 is a top or plan view of the same; Fig. 3 is a partial longitudinal central section through the same, showing the material looping mechanism, together with the means for delivering the looped material to the bunching and securing head, said view being drawn on an enlarged scale; Fig. 4 is a horizontal section, taken on line 4—4 in Fig. 3; Fig. 5 is a fragmentary transverse section, on a considerably enlarged scale, taken on line 5—5 in Fig. 1; Fig. 6 is an enlarged fragmentary horizontal 50 section through the looping mandrel, show-

ing the means for shifting the looped material thereon, and the means for delivering required portions of the looped material to the bunching and securing head; Fig. 7 is an enlarged vertical central section through the bunching and securing head; and Fig. 8 is a view similar to that of Fig. 7, but showing certain operations of the bunching and securing head.

Similar characters of reference are employed in the above described views to indicate corresponding parts.

Referring to the drawings, the reference character 1 indicates the bed-frame of the machine, the same being supported by the legs 2. Mounted in bearings 3, to extend longitudinally along one side of the bed-frame 1, is a drive-shaft 4, having at one end driving pulleys 5 adapted to be belt driven from any suitable source of power. It will be understood, however, that said drive-shaft 4 may be driven in any other way, as may be expedient.

Fixed upon said bed-frame are a pair of longitudinally spaced upstanding pedestals 6. Fixed in said pedestals, to extend longitudinally forward therefrom, is a tubular housing 7. Rotatably mounted upon the forward end portion of said housing 7, preferably on anti-friction bearing means 8, is a spool-hub 9 having at one end a sprocket 10. A sprocket and chain drive 11 actuated by said drive-shaft 4 and cooperative with said sprocket 10 rotates the spool-hub 9. Detachably mounted on said spool-hub 9, so as to be rotated thereby, is a spool 12 upon which is wound a supply of strand material, as e. g. metallic gimped strand material G. Connected with the annular abutment flange 9' of the spool-hub 9, against which the spool 12 is locked, are one or more outwardly projecting lugs 13, to which are releasably bolted fastening clips 14, which are caused to clamp the peripheral portion of the adjacent end flange of the spool 12, to thereby rigidly couple said spool with the spool-hub so that the former rotates with the latter. Mounted on said housing 7, adjacent to the forward end of the spool-hub 9, is an anti-friction bearing means 15, upon which is

freely rotatable a flier ring 16 from which projects a take-off arm 17, having a perforate end portion through which the gimped strand G leads from the spool 12. Also connected with said flier ring 16 is a forwardly projecting winder arm 18, having a perforate end portion through which the gimp strand G extends to the looping mandrel of the machine. Connected with the inner end 10 of the flier ring 16 is a spring arm 16' which frictionally engages the adjacent end of the spool-hub 9, whereby the flier ring is driven by the spool hub, but is free to slip relative thereto under the pull of the gimp strand 15 G.

The reference character 19 indicates the looping mandrel of the machine, the same having an enlarged cylindrical butt portion 20 which is internally threaded to screw up- 20 on the forward end of the housing 7, the latter being threaded to receive the same. Said butt portion 20 is preferably provided at its forward end with a conical or forwardly and inwardly inclined shoulder 21 25 leading to the surface of the mandrel 19. The mandrel 19 is preferably of substantially oval cross-sectional shape, as shown in Fig. 5, and is also longitudinally tapered toward its forward free end. The mandrel 19 30 is provided with an axial passage or bore 22, which is aligned with the bore of said tubular housing 7. The top and bottom sides of said mandrel 19 are provided with slotted ways 23, leading from a point forwardly 35 spaced from the butt portion 20 to the free end of the mandrel. Connected with the top and bottom sides of the mandrel, intermediate the slotted ways 23 and the butt portion 20, are laterally spaced apart, longitudinally disposed, outwardly and upwardly 40 chamfered ribs 24. Rotatably mounted in the ends of bearing brackets 25, so as to be respectively disposed one above and one below the mandrel 19 where said ribs 24 are 45 located, are brush wheels 26, each having grooved pulley 27 connected with their hubs. Said bearing brackets 25 extend from a swivel post 28, which is also provided with a yoke bearing 29 in which are mounted driv- 50 en pulleys 30. Said post is mounted to turn in a supporting bracket 31 fixed to the side of the bed-frame 1. A belt and pulley drive 32, actuated by the drive-shaft 4 engages and drives the driven pulleys 30, which in 55 turn drive belts 33 which respectively run over the pulleys 27 of the brush wheels 26 to drive the same (see more especially Fig. 5). The swivel post 28 may be turned by the lever-bar 34 to dispose the brush wheels 60 26 in operative relation to the mandrel 19, being locked in such position by a lock-pin 65 engaged through the lever-bar 34 and a perforate anchor lug 36 which is fixed to the side of the bed-frame 1. When it is desired to remove an empty strand supply

spool 12, to replace the same with a full spool, the swivel post 28 may be released and turned to swing the brush-wheels 26 away from the mandrel, so as to permit the spools 12 to be taken off and on over the mandrel. In order to displace the take-off arm 17 of the flier ring 16, so as to permit the spools 12 to pass over the same as they are taken on or off the spool-hub 9, said take-off arm 75 is pivotally connected with the flier ring so as to fold down over the mandrel.

During operation of the machine, the rotation of the spool-hub 9 in turn rotates the supply spool 12, and through the frictional driving connection afforded by the spring arm 16', the flier ring 16, with its take-off and winder arms, is also rotated in a self-compensating manner as the gimped strand G pays off of the spool 12 and passes through said take-off and winder arms to the mandrel. The revolution of the winder arm 18 carries the gimped strand G around the mandrel 19 close to the butt portion 20, the inclined shoulder 21 of the latter serving to guide the gimped strand G to, around and upon the mandrel, to thus loop the material upon itself by forming running convolutions thereof around the mandrel.

Means is provided for feeding the convolutions of gimped strand formed on the mandrel forwardly along the same. This means comprises the following mechanism:

Formed in opposite sides of the housing 7 and continued through the butt portion 20 and along opposite sides of the mandrel 19 are longitudinal guideways 37 in which are slidably mounted, for reciprocatory longitudinal movement, slide-bars 38. Pivotally connected with the forward free ends of said slide-bars 38 are slotted carrier-bars 39, which ride in those portions of said guideways 37 which lie along the sides of the mandrel. Laterally movable in the slots of said carrier-bars 39 are gripper jaws 40 provided, along their outer longitudinal margins, with forwardly projected serrations or teeth 41. Said gripper jaws are coupled with the carrier-bars 39 by pins 42 which extend through oblique cam-slots 43 with which the gripper jaws are provided. When the side-bars 38 and carrier-bars 39 start forward, during their reciprocatory operation, the cam-slots 43 riding off the pins 42 produce an initial laterally outward bodily movement of said gripper jaws 40, whereby the teeth 41 thereof are projected outwardly between the convolutions of gimped strand G formed on the mandrel 19, so as to positively engage the latter, whereupon continued forward movement of the gripper jaws will operate to propel or shift the formed convolutions forwardly along the tapered mandrel. When the slide-bars 38 and carrier-bars 39 start rearward, during their reciprocatory operation, the cam-slots 120

43 riding in opposite direction upon the pins 42 produce an initial laterally inward bodily movement of said gripper jaws 40, whereby the teeth 41 thereof are retracted inwardly 5 so as to be disengaged from the convolutions of gimped strand G, whereupon rearward movement of the gripper-bars takes place without tendency to retract the forwardly shifted convolutions of said strand. Suitable 10 means are provided for producing desired reciprocatory movement of said slide-bars 38, carrier-bars 39 and gripper jaws 40, the same comprising, in one possible form, a transverse counter shaft 44 journaled in 15 the bed-frame 1. Fixed on said counter-shaft 44 is a worm gear wheel 45, with which meshes a drive worm 46 actuated by said drive-shaft 4. Fixed to and extending between said pedestals 6 are longitudinal 20 track-bars 47, on which are slidably arranged slide-blocks 48 to which the rearward ends of said slide-bars 38 are suitably secured.

Journalized in and across the bed-frame 1 is a rock-shaft 49, to which is fixed an upwardly projecting lever arm 50 having at its free end a yoke-portion 51 to straddle the housing 7 and track-bars 47, the free bifurcated ends of said yoke-portion 51 being respectively pivotally engaged with outwardly projecting studs 52 with which the slide-blocks 48 are provided. Also fixed on said rock-shaft 49 is a downwardly projecting lever arm 53. Pivoted on a fulcrum bracket 54 depending from said bed-frame 35 1 is an actuating lever 55 having at its upper free end a nosing 56 engageable by a star cam 57, which is fixed on and rotated by said counter-shaft 44. Said actuating lever 55 is operatively interconnected with said lever 40 arm 53 by a link 58. Rotation of said star cam 57 operates, through the described lever system, to swing forwardly the lever arm 50, whereby forward movement of said slide-blocks 48 and the slide-bars 38, carrier-bars 45 39 and gripper jaws 40 is caused to produce gimp strand shifting strokes of the latter. Retraction of these parts, upon presentation of the low points of the star-cam 57 relative to the actuating lever 55, is accomplished by 50 the pull spring 59, which is connected between the lever arm 53 and an anchor-piece 60 on the bed-frame 1.

As the convolutions of gimped strand G formed about the mandrel pass beneath the brush-wheels 26, the peripheries of which are preferably formed by wire bristles, portions of the metallic or other gimping convolved about the carrier strand, are swept or crowded outwardly along the carrier strand 55 and over one or the other of the ribs 24, thus more or less tightly stretching the gimping along portions of the carrier strand intermediate looped ends or sides thereof, and providing attenuated gimped strand portions 60 between said looped ends or sides,

which may be more closely bunched and consolidated when forming the central core or heart of the finished device, and in accordance with certain of the principles of construction of the finished device as fully disclosed in my aforementioned United States Letters Patent No. 1,713,975 of May 21st, 1929.

After the convolutions of gimped strand have been treated by the brush wheels 26, for the purposes and in the manner above described, and have been shifted forwardly upon the mandrel 19 beyond said brush-wheels, means is provided for grasping a predetermined quantity of the convolutions, and thereupon delivering the same along the mandrel to a bunching and securing head, which functions to bunch together and secure the attenuated portions of the convolutions intermediate the looped ends thereof, to thus form the core or central heart of the finished device from which said looped ends radiate in various directions. This delivery means comprises a reciprocable plunger 61 which extends axially through the tubular housing 7 and into the passage or bore 22 of the mandrel 19. Suitably timed longitudinal reciprocation of said plunger 61 is attained by the following mechanism. Fixed on said counter-shaft 44, so as to be rotated thereby, is a cam-wheel 62, and pivotally mounted at the rear end of bed-frame 1, by a fulcrum shaft 63, is a lever member 64, the lower arm of which carries an anti-friction roller 65, operatively engaged by the periphery of said cam-wheel 62. The upper arm of said lever member 64 is pivotally connected with a cross-head 66 to which the rearward end of said plunger 61 is attached; said cross-head being slideable on guide tracks 67 connected with the bed-frame 1. Said plunger 61 is forwardly moved by the thrust of said cam-wheel 62 upon the lever member 64, but is retracted by a weight 68 connected by a flexible cable 69 or the like with said cross-head 66; said cable 69 running over an idler pulley 70 journaled on a bracket support 71 at the rear end of said bed-frame 1. It will be understood, however, that any other suitable means may be employed for producing the retractive movement of said plunger 61. Pivotally connected with and at opposite sides of a nose block 72, affixed to the forward end of said plunger 61, are pairs of inwardly yieldable outwardly and forwardly projecting angular push-fingers 73, having oppositely divergent tail-pieces 73' interconnected by spring means 74, whereby the push-fingers are turned to normally project angularly outward through the slotted ways 23 of the mandrel 19, but so as to yield to any in-swinging pressure applied thereto.

Slidably mounted on said bed-frame 1 in opposition to said mandrel 19, and movable

120

125

130

toward and from the free end of the latter, is a bunching and securing head, comprising a base 75 longitudinally movable on ways 76. Said base is provided with a rack 77 which meshes with a pinion 78 mounted on a transverse shaft 79 journaled in and extending transversely of said bed-frame.

One end of said shaft 79 is provided with a crank handle 80. By turning said handle 80, the rack and pinion can be actuated to slide said base 75, and the mechanism carried thereby, up to and in operative relation to the free end of the mandrel 19, or so as to withdraw the mechanism from the free end of the mandrel 19 to provide clearance for putting on and off gimp strand supply spools 12 over the mandrel, to mount or dismount the same relative to the spool-hub 9. Extending upwardly from said base 75 are transversely spaced upstanding bearing plates 81, between which is suitably mounted a bracket member 82. Fixed on the end of said bracket-member 82 which is opposed to the mandrel 19, and in axial alignment with the latter, is a backing member 83 having an indented V-shaped receiving portion 84 in the apex of which is a seat 85. A tie-wire guiding bore 86 extends through said backing member 83 to said seat 85; and connected with said backing member 83 in alignment with said bore 86 is a stationary cutter element 87 of tempered steel, and bored to pass tie-wire material therethrough. Pivoted to said bracket member 82 for vertical swing, is a movable cutter arm 88, having at its free end a cutter element 89 to cooperate with the cutter element 87, said arm 88 and element 89 being bored to pass tie-wire material therethrough. Said movable cutter arm 88 and its cutter element 89 is normally but yieldably upheld against an adjustable stop 90, whereby the bores thereof are normally aligned with the bores of said stationary cutter element 87 and backing member 83; this being accomplished by a pull-spring 91 which is anchored to a bridge strap 92 extending between the bearing plates 81. A pair of intergeared feed-rolls 93 are arranged behind the cutter mechanism to feed tie-wire T from a suitable source of supply, such e. g. as the supply reel 94 mounted on the supporting bracket 95 at the adjacent end of the bed-frame 1. Said tie wire T runs from said reel to the feed rolls over a guide roller 96 carried on a supporting post 97, and the tie-wire extends through the cutting mechanism to the seat 85 of the backing member 83. The means for driving said feed-rolls 93 with timed intermittent movement, comprises a transverse shaft 98, journaled in and extending transversely of said bearing plate 81. Actuated by the drive-shaft 4 is a worm 99 which meshes with and drives a worm gear 100 fixed on an end of said shaft

98. Fixed on the opposite end of said shaft 98 is the driving member 101 of a geneva or intermittent gearing, the driven member 102 of which is fixed on a shaft of one of the feed rolls 93. The shafts of said feed rolls are driven, one from the other, by intermeshing gearing 103 connected therewith.

The means for producing properly timed tie-wire severing movement of said movable cutter arm 88, comprises a pivoted lever 104, coupled to the free end of said cutter arm 88 by a link 105. Said lever 104 is provided with a lateral stud or projection 106 which engages and rides on the periphery of a cutter control cam 107; the latter being fixed on and rotated by said transverse shaft 98. A strong pull-string 108 interconnected between the free end of said lever 104 and the base 75 exerts a yieldable downward bearing of said lever stud or projection 106 upon the periphery of the cam 107.

In the operation of the machine, at properly timed intervals, as controlled by its actuating cam-wheel 62, the plunger 61 is thrust forwardly, whereby the push-fingers 73 are thrust through the top and bottom portions of the convolutions of gimped strand G forwardly shifted on the mandrel 19 at points intermediate the looped ends formed thereby, and behind a quantity thereof sufficient to provide the individual device to be formed therefrom, whereupon forward movement of the plunger 61 and push-fingers 73 slides forwardly and off the end of the mandrel 19 the thus segregated quantity of such gimped strand convolutions. As these selected convolutions are slid off the mandrel 19, the central portions thereof are engaged by the V-shaped receiving portions 84 of the bunching and securing means, so as to be guided to and consolidated together in and upon the seat 85, being held therein by the nose-block 72 of the plunger 61, thus forming a central core or heart from which the looped ends of the gimped strand may extend. Preferably, prior to the time the gimped strand material is finally engaged and compacted between the seat 85 and nose-block 72, the tie-wire feeding means is timed to operate, whereby the tie-wire T is thrust through the cutting mechanism, so that its leading end will pierce transversely through the core forming portions of said gimped strand G, when bunching together thereof is completed. When the tie-wire T is so positioned, the cutting mechanism is actuated by the withdrawal of the drop-step 107 of the cam 107 from the stud or projection 106, whereupon the spring 108 sharply and forcefully swings down the lever 104, to in turn swing down the cutter arm 88 so that its cutter element 89 moves shearingly relative to the cutter element 87 thus severing the tie-wire, while at the same time causing the shoulder of cutter element 89 to back the

severed end of the cut-off length of said tie-wire to hold the same against back thrusting pressure. While the severed length of tie-wire is thus held, the plunger 61 completes its delivery thrust, whereby not only is the gimped strand compactly consolidated between the seat 85 and nose-block 72, but the latter is caused to strike the projecting end of the tie-wire emerging through the bunched portions of said gimped strand so as to laterally turn over the same to hold it against withdrawing from its penetrating relation to said bunched portions of said gimped strand.

15 As the convolutions of gimped strand G are delivered off of the mandrel 19 and the attenuated central portions thereof bunched together around the penetrating end of the tie-wire T as above explained, the looped end portions of the gimped strand projecting from opposite sides of the bunched core or heart, are respectively engaged over a rotating mechanism, adapted to rotate the mass of convolutions, to tightly wind the tie-wire 20 around the bunched core or heart in strong core retaining relation thereto. Prior to this operation, however, the operator severs, preferably by hand snips or shears, the gimped strand which pulls out and extends 25 between the delivered quantity of convolutions thereof and the convolutions remaining on the mandrel, tucking the loose end back into the latter so as to hold the same against unwinding.

30 The rotating mechanism for winding on the tie-wire comprises the following mechanism:—

35 Journalled in the respective bearing plates 81, to extend respectively toward opposite sides of said backing member 83, are spindles 109, on the inner ends of which are horns 110, the free ends of which normally align themselves with the discharge end of the mandrel, preferably entering indented slots 110'. As the convolutions of gimped strand are discharged from the mandrel, in the manner already explained, the free looped ends thereof engage over said horns 110, the latter having outwardly off-set portions back of their free ends upon which the extremities of said looped ends ride, so as to draw out the latter into comparatively narrow loop portions. When the looped ends are thus engaged, and the tie-wire T and core portions joined, said horns are automatically rotated, thus rotating the convolutions of gimped material so as to wind the length of tie-wire T tightly around the bunched core portions thereof, to secure the latter in a permanent consolidated condition, whereby the loop ends may extend freely therefrom in various directions, when removed from the rotating horns, in accordance with the requirements of the finished

device. The means for producing the properly timed turning movement of the horns, comprises a transverse shaft 111 journaled in and between said bearing plates 81 below said backing member 83. Fixed on said shaft 111 is a pinion 112 which meshes with a longitudinally reciprocable driving rack 113 suitably supported and guided, as by the roller 114 on which its forward end rides, and by a roller 115 carried by its rearward end to ride on a trackway 116. Timed actuating thrust of said driving rack is effected by a cam 117 mounted on and turned by said shaft 98. Fixed on the shaft 111 is a drum 118, to which is attached a pull cable 119 carrying a gravitatable weight 120 at its free end. Also fixed on said shaft 111 are gear wheels 121 which respectively mesh with and drive pinions 122 on said spindles 109. Outward thrust of said rack 113 under the push of said cam 117 against the roller 115 rotates, through the described transmission means, said horns 110, while at the same time winding up the pull cable 119 on the drum 118. As the drop of said cam 117 passes the roller 115, the rack is freed for return movement through the reverse rotation of the shaft 111 by the gravitation of the weight 120 which pulls the wound cable 119 off the drum with reverse rotating effect thereupon and upon said shaft 111. The reverse rotation of said shaft 111, also reversely rotates the spindles and horns to return the same to initial normal positions. The cam 117 may be so shaped to cause the horns 110 to dwell for a short period of time, and before aligning themselves with the mandrel 19, in either a somewhat upturned or downturned position, to permit the fabricated device to be removed therefrom, either by the hand of the operator or by automatic take-off means (not shown).

Upon completion of the tie-wire winding operation, the plunger 61 is retracted preparatory to delivery of the next succeeding quantity of gimped strand convolutions to be operated upon. As the plunger is retracted the inclined push-fingers 73 yield inwardly when engaging the convolutions on the mandrel 19, so as to pass under the same in returning to initial position.

From the above description, it will be apparent that the machine of the present invention is adapted to automatically fabricate the described articles from a running strand of material. While I have shown the machine as adapted to operate upon metal gimped strand material, it will be obvious that the same is as well adapted to operate upon any other flexible cord-like strand, whether metal gimped or not.

As many changes could be made in the above described construction and many apparently widely different embodiments of

this invention could be made without departing from the scope thereof as claimed; it is intended, therefore, that all matter contained in the above description or shown in 5 the accompanying drawings shall be interpreted as illustrative and not in a limiting sense.

I claim:—

1. An automatic machine of the kind described, comprising a mandrel, power actuated means to wind flexible material in convolutions about said mandrel to form looped ends, timed means to discharge a segregated quantity of the wound convolutions 10 from the mandrel, means to receive the discharged convolutions adapted to bunch together the portions thereof intermediate their oppositely extending loop ends, and power actuated means to apply a tie-wire 15 about said bunched portions.

2. A machine of the kind described, comprising a mandrel, means to wind flexible material in convolutions about said mandrel to form looped ends, means to discharge a segregated quantity of the wound convolutions 20 from the mandrel, means to receive the discharged convolutions adapted to bunch together the portions thereof intermediate their oppositely extending loop ends, means 25 cooperative with said receiving means to supply a tie-wire having its inner end penetrated through said bunched portions, and rotative means to engage the loop ends of the discharged convolutions for rotating the 30 mass thereof so as to wind the outer end of said tie-wire about said bunched portions.

3. A machine of the kind described, comprising a mandrel, means to wind a metal gimped strand in convolutions about said 35 mandrel to form looped ends, means cooperative with said mandrel for stretching the metal gimping on the portions of the strand convolutions intermediate the oppositely extending loop ends thereof to form central attenuated portions, means to discharge a segregated quantity of the thus treated convolutions, means to receive the discharged convolutions adapted to bunch the central attenuated portions thereof together, and 45 means to apply a tie-wire about said bunched portions.

4. A machine of the kind described, comprising a mandrel, means to wind a metal gimped strand in convolutions about said 50 mandrel to form looped ends, means cooperative with said mandrel for stretching the metal gimping on the portions of the strand convolutions intermediate the oppositely extending loop ends thereof to form central attenuated portions, means to discharge a segregated quantity of the thus treated convolutions, means to receive the discharged convolutions adapted to bunch the central attenuated portions thereof together, means 55 cooperative with said receiving means to

supply a tie-wire having its inner end penetrated through said bunched portions, and rotative means to engage the loop ends of the discharged convolutions for rotating the mass thereof so as to wind the outer end of said tie-wire about said bunched portions. 70

5. A machine of the kind described, comprising a mandrel having a free end, means to wind flexible material in convolutions about said mandrel to form looped ends, reciprocable means cooperative with said mandrel to discharge from the free end thereof a segregated quantity of the wound convolutions, and means to receive the discharged convolutions adapted to bunch together the portions thereof intermediate their oppositely extending loop ends ready to receive application of binding means thereto. 75

6. A machine of the kind described, comprising a mandrel having a free end, means to wind a metal gimped strand in convolutions about said mandrel to form looped ends, means cooperative with said mandrel for stretching the metal gimping on the portions of the strand convolutions intermediate the oppositely extending loop ends thereof to form central attenuated portions, reciprocable means cooperative with said mandrel to discharge from the free end thereof a segregated quantity of the wound and thus treated convolutions, and means to receive the discharged convolutions adapted to bunch together in compact relation the attenuated portions of said discharged convolutions intermediate their oppositely extending loop ends ready to receive application of binding means thereto. 80

7. A machine of the kind described, comprising a fixed support, a mandrel connected with one end of said support, a driven spool-hub rotatably mounted on said support adjacent to said mandrel, said spool-hub being adapted to receive and rotate a spool containing a supply of flexible material to be fabricated, a rotatable flier ring having winding means through which the flexible material is threaded, said winding means being adapted to revolve around said mandrel to wind the flexible material thereabout so as to form looped ends, self-compensating driving means between said spool-hub and flier ring, means to discharge a segregated quantity of convolutions of applied flexible material from said mandrel, and means to receive the discharged convolutions adapted to bunch together the portions thereof intermediate their oppositely extending loop ends ready to receive application of binding means thereto. 85

8. A machine of the kind described, comprising a fixed support, a mandrel connected with one end of said support, a driven spool-hub rotatably mounted on said support adjacent to said mandrel, said spool-hub being 90

adapted to receive and rotate a spool containing a supply of flexible material to be fabricated, a rotatable flier ring having winding means through which the flexible material is threaded, said winding means being adapted to revolve around said mandrel to wind the flexible material thereabout so as to form looped ends, self-compensating driving means between said spool-hub and flier ring, means to discharge a segregated quantity of convolutions of applied flexible material from said mandrel, means to receive the discharged convolutions adapted to bunch together the portions thereof intermediate their oppositely extending loop ends, means cooperative with said receiving means to supply a tie-wire having its inner end penetrated through said bunched portions, and rotative means to engage the loop ends of the discharged convolutions for rotating the mass thereof so as to wind the outer end of said tie-wire about said bunched portions.

9. A machine of the kind described, comprising a fixed support, a mandrel connected with one end of said support, a driven spool-hub rotatably mounted on said support adjacent to said mandrel, said spool-hub being adapted to receive and rotate a spool containing a supply of metal gimped strand to be fabricated, a rotatable flier ring having winding means through which the strand is threaded, said winding means being adapted to revolve around said mandrel to wind the strand thereabout so as to form looped ends, self-compensating driving means between said spool-hub and flier ring, means cooperative with said mandrel for stretching the metal gimping on the portions of said strand convolutions intermediate the oppositely extending loop ends thereof to form central attenuated portions, and means to discharge a segregated quantity of thus treated convolutions from said mandrel, and means to receive the discharged convolutions adapted to bunch together said attenuated portions thereof ready to receive application of binding means thereto.

50 10. A machine of the kind described, comprising a fixed support, a mandrel connected with one end of said support, a driven spool-hub rotatably mounted on said support adjacent to said mandrel, said spool-hub being adapted to receive and rotate a spool containing a supply of metal gimped strand to be fabricated, a rotatable flier ring having winding means through which the strand is threaded, said winding means being adapted to revolve around said mandrel to wind the strand thereabout so as to form looped ends, self-compensating driving means between said spool-hub and flier ring, means cooperative with said mandrel for stretching the metal gimping on the por-

tions of said strand convolutions intermediate the oppositely extending loop ends thereof to form central attenuated portions, means to discharge a segregated quantity of thus treated convolutions from said mandrel, means to receive the discharged convolutions adapted to bunch together said attenuated portions, means cooperative with said receiving means to supply a tie-wire having its inner end penetrated through said gathered attenuated portions, and rotative means to engage the loop ends of the discharged convolutions for rotating the mass thereof so as to wind the outer end of said tie-wire about said gathered attenuated portions.

11. A machine of the kind described, comprising a fixed housing having an axial passage therethrough, a mandrel connected with and longitudinally projecting from one end of said housing, said mandrel having an axial passage communicating with said housing passage, means to wind flexible material in convolutions about said mandrel to form looped ends, a plunger reciprocable through the aligned passages of said housing and mandrel, yieldable angularly projected push-fingers on said plunger to engage, segregate and discharge a quantity of formed convolutions from the mandrel, and means to receive the discharged convolutions adapted to bunch together the portions thereof intermediate their oppositely extending loop ends ready to receive application of binding means thereto.

12. A machine as defined in claim 11, in which said means to wind the material about the mandrel comprises, a spool-hub for mounting a supply of material, said spool-hub being rotatably mounted on said housing adjacent to said mandrel, means to drive said spool-hub, a rotatable flier ring having winding means through which the material is threaded, said winding means being adapted to revolve around said mandrel, and self-compensating driving means between said spool-hub and flier ring.

13. A machine as defined in claim 11, in which said means to wind the material about the mandrel comprises, a spool-hub for mounting a supply of material, said spool-hub being rotatably mounted on said housing adjacent to said mandrel, means to drive said spool-hub, a rotatable flier ring having winding means through which the material is threaded, said winding means being adapted to revolve around said mandrel, and a frictional connection between said spool-hub and flier ring to provide for yieldably driving the latter from the former.

14. In a machine of the kind described, a mandrel having an axial passage therethrough, means to wind flexible material in convolutions about said mandrel, means reciprocable along the sides of the mandrel to

- shift the applied convolutions along the same, a plunger reciprocable in the axial passage of the mandrel, yieldable angularly projected push-fingers on said plunger to engage, segregate and discharge a quantity of formed convolutions from the mandrel, and said mandrel having ways through the walls thereof to accommodate the movements of said push-fingers.
- 10 15. In a machine of the kind described, a mandrel having an axial passage therethrough, means to wind flexible material in convolutions about said mandrel to form looped ends, means reciprocable along the 15 sides of the mandrel to shift the applied convolutions along the same, a plunger reciprocable in the axial passage of the mandrel, yieldable angularly projected push-fingers on said plunger to engage, segregate and discharge a quantity of wound convolutions from the mandrel, said mandrel having ways through the walls thereof to accommodate the movements of said push-fingers, means to receive and bunch together 20 the central portions of the discharged convolutions, means cooperative with said receiving means to supply a tie-wire having its inner end penetrated through the bunched portions of the discharged convolutions, and rotative means to engage the loop ends of the discharged convolutions for rotating the mass thereof so as to wind the outer end of said tie-wire about said central bunched portions.
- 25 30 35 40 45 50 55 60 65 70 75 80 85 90 95 100 105 110 115 120 125 130
16. In a machine of the kind described, a mandrel having an axial passage therethrough, means to wind a metal gimped strand in convolutions about said mandrel, means cooperative with opposite faces of said mandrel for stretching the metal gimping on the portions of said strand convolutions intermediate oppositely extending loop ends thereof to form central attenuated portions, means reciprocable along the sides of the mandrel to shift the applied convolutions past said stretching means, a plunger reciprocable in the axial passage of said mandrel, yieldable angularly projected push-fingers on said plunger to engage, segregate and discharge a quantity of formed convolutions from the mandrel, and said mandrel having ways through the walls thereof to accommodate the movements of said push-fingers.
17. In a machine of the kind described, a mandrel having an axial passage therethrough, means to wind a metal gimped strand in convolutions about said mandrel, means cooperative with opposite faces of said mandrel for stretching the metal gimping on the portions of said strand convolutions intermediate oppositely extending loop ends thereof to form central attenuated portions, means reciprocable along the sides of the mandrel to shift the applied convolutions past said stretching means, a plunger reciprocable in the axial passage of said mandrel, yieldable angularly projected push-fingers on said plunger to engage, segregate and discharge a quantity of formed convolutions from the mandrel, said mandrel having ways through the walls thereof to accommodate the movements of said push-fingers, and means to receive the discharged convolutions adapted to bunch together said attenuated portions thereof ready to receive application of binding means thereto.
18. In a machine of the kind described, a mandrel having an axial passage therethrough, means to wind a metal gimped strand in convolutions about said mandrel, means cooperative with opposite faces of said mandrel for stretching the metal gimping on the portions of said strand convolutions intermediate oppositely extending loop ends thereof to form central attenuated portions, means reciprocable along the sides of the mandrel to shift the applied convolutions past said stretching means, a plunger reciprocable in the axial passage of said mandrel, yieldable angularly projected push-fingers on said plunger to engage, segregate and discharge a quantity of formed convolutions from the mandrel, said mandrel having ways through the walls thereof to accommodate the movements of said push-fingers, and means to receive the discharged convolutions adapted to bunch together said attenuated portions, means cooperative with said receiving means to supply a tie-wire having its inner end penetrated through said gathered attenuated portions, and rotative means to engage the loop ends of the discharged convolutions for rotating the mass thereof so as to wind the outer end of said tie-wire about said gathered attenuated portions.
19. In a machine of the kind described, a mandrel, means to wind flexible material in convolutions about said mandrel, means to discharge a segregated quantity of formed convolutions from the mandrel, a fixed backing plate having a V-shaped receiving portion provided with a seat opposed to said mandrel and its discharging means, means to feed tie-wire material for projection into the central portion of aggregated convolutions disposed on said seat, means to sever the tie-wire material to provide a tie-wire element, and rotative means on opposite sides of said backing plate to engage through the loop ends of discharged aggregated convolutions to rotate the mass thereof to wind the tie-wire element about the central portions thereof, and means to actuate said rotative means.
20. In a machine of the kind described, a mandrel having an axial passage therethrough, means to wind flexible material in convolutions about said mandrel, a plunger

reciprocable in the axial passage of the mandrel, means carried by said plunger to engage, segregate and discharge a quantity of formed convolutions from the mandrel, a backing plate having a V-shaped receiving portion provided with a seat opposed to the discharge end of said mandrel and aligned with said plunger, said plunger operating to compactly consolidate the central portions of discharged convolutions upon said seat ready for application of binding means thereo.

21. In a machine of the kind described, a mandrel having an axial passage therethrough, means to wind flexible material in convolutions about said mandrel, a plunger reciprocable in the axial passage of the mandrel, means carried by said plunger to engage, segregate and discharge a quantity of formed convolutions from the mandrel, a backing plate having a V-shaped receiving portion provided with a seat opposed to the discharge end of said mandrel and aligned with said plunger, said plunger operating to compactly consolidate the central portions of discharged convolution upon said seat, means to feed tie-wire material for projection into the consolidated central portion of said discharged convolutions, and rotative means to engage the loop ends of discharged convolutions to rotate the mass of the latter to wind the tie-wire about the consolidated central portions thereof.

22. In a machine of the kind described, a mandrel having an axial passage therethrough, means to wind flexible material in convolutions about said mandrel, a plunger reciprocable in the axial passage of the mandrel, means carried by said plunger to engage, segregate and discharge a quantity of formed convolutions from the mandrel, a backing plate having a V-shaped receiving portion provided with a seat opposed to the discharge end of said mandrel and aligned with said plunger, said plunger operating to compactly consolidate the central portions of discharged convolutions upon said seat, means to feed tie-wire material for projection into the consolidated central portion of said discharged convolutions, means to sever the tie-wire material to provide a tie-wire element, and rotative means on opposite sides of said backing plate to engage through the loop ends of discharged convolutions to rotate the mass thereof to wind the tie-wire element about the consolidated central portions thereof.

In testimony, that I claim the invention set forth above I have hereunto set my hand

60 this 23rd day of June, 1931.

DANIEL J. MAYER.
